PROCESS OF METAL ATTENUATION

Martin E. Evans, Kankakee, Ill.

Application June 5, 1941, Serial No. 396,788

29 Claims. (Cl. 29—155.41)

This invention relates to the attenuation of material, and particularly to a process of multiple attenuation in the sense that a number of strands are handled and attenuated at the same time in a group arrangement.

The primary object of this invention is to provide a process of drawing a number of wires whereby the handling and the number of dies are reduced to a minimum.

Another object of the improved process is to provide for drawing a group of wires simultaneously through a die in such a manner as to automatically secure to each wire a proportionate reduction of the original cross-section of each wire of the group, and to preserve to each wire its cross-sectional shape.

A further object of the process is to provide for elongating wires of different cross-sectional shapes simultaneously through a die shaped independently of the wire cross-section.

Another object of the process is to provide for changing the shape of selected portions of the cross-section of a wire and of a plurality of wires simultaneously in a die.

In another aspect, this process contemplates providing for flexibly bonding together a plurality of wires and for removing the bonding medium incidentally to effecting the elongation of the wires.

In still another aspect, the process contemplates providing heat treatment of the wire incidental to wire drawing.

In its broadest aspect, the process contemplates bonding a number of strips together, attenuating the strips in a group, removing the bonding means wholly or partially from the wires resulting from the strips and the utilization of the grouped position of the wires for further processing of a different kind, such as twisting and insulating to form an insulated electric conductor.

The various objects are attained by employing in series arrangement, metal coating apparatus, attenuating apparatus, wire accumulating and heat treating apparatus so coordinated in their operation that the continuity of operations on the material in its passage through the series is uninterrupted. The first mentioned object is accomplished by causing a number of strips, with surfaces suitably conditioned for coating with molten metal of a melting temperature lower than that of the strip metal, to pass through a body of the coating metal and to assume a closely grouped position with coating metal between strips, effective to bond them into a solid body. The handling and threading through dies then

becomes only the handling and threading through the number of dies required for the reduction of a single wire of a length of a single wire of the group, and of a weight of the whole number of wires of the group. If seven round wires, all of the same size, are passed through the bath of coating metal and removed therefrom in closely grouped position with one wire as a center, and sufficient bonding metal attached between the

10 wires to form a solid cylindrical body of metal with the wires, the body of metal may be attenuated in a graduated series of dies for a round wire, each wire held in the cylindrical body receiving its proportionate reduction in each die. Various 15 means for so grouping and bonding the wires for attenuation are available, particular preference being given to a device which comprises a coating metal bath, a die immersed in the coating metal on one face, with cooling means on the opposite face, and heating means intermediate thereof, and a traction drum of a wire drawing machine, all operative so that say seven round wires of equal size apart from each other upon entering the metal bath at one end emerge therefrom at 20 the opposite end, grouped together through a round die with bath metal attached between the wires as a solid body to the form of the die, by reason of the die cooling and the traction furnished by the drawing drum.

30 In the attainment of the second object of this invention, in addition to the use of relatively soft and low melting material for filling in between the wires, provision is made use of to assure joint passage of wire and filler through the attenuating die which is the subject of a separate patent. The special provision is in the nature of a long approach passage and a long exit passage with the tapered reducing section of the die in between. Thus the reducing die, not shown in detail, has an 35 approaching tube long enough to accommodate lubricating material and bonded strips and to restrain any backward flow tendency of the bonding material. The die also has an exit passage long enough to restrain any forward flow of the bonding material ahead of the elongating wires. This die construction eliminates the necessity for a holding casing around the filling material between the wires and gives free passage for placement and removal of the filler material. With the elimination of the holding casing around the wires and filler, progressive placement, attenuation, and removal of filler is feasible.

40 As an example of a suitable bonding metal, zinc may be used. It unites readily with ferrous base metals, and is electropositive and acts as a lubri-

cant. After the bonding operation with zinc is performed, as previously described, the residual heat of the coating operation is not allowed to fall below a point having a temperature of 150° F., while higher temperatures, ranging up to or approaching plasticity of the zinc, are sometimes desirable, as the thickness of the bonding metal section increases. Usually a working temperature in the vicinity of 300° F. is satisfactory. The repeated elongation of the zinc strip through dies at such temperatures gives the zinc coating pliability and ductility greatly in excess of like qualities in unworked zinc coatings of various thicknesses. An individual wire so coated and attenuated has a greater protection value, by reason of the pliability and ductility accompanying a greater and uniform thickness of zinc on the wire.

As an example of changing the shape of selected sections of the cross-section of a wire and of a plurality of wires simultaneously, again consider a group of seven round wires, all of the same size, grouped together with six of the wires around a center wire, emerging from a bath of zinc through a die fitting closely the outer contour around the wires with bath metal bonding the wires together interiorly. The bonded group of wires, when passed through a series of round reducing dies, spreads circumferentially and shrinks diametrically to fill the valleys between the wires until a solid body of metal fills a die, after which the wire elongates during further passage through dies. The cross-sectional shape of the circumferential wires consequently changes from round to keystone shape, with the outer circumference fitting to the die circle. Further reductions of the group of wires secures to the round center wire, and to the circumferential keystone wires, their proportionate percentage of reduction.

In the manufacture of lamp cord for electric lamps, No. 30 gage B. & S. copper wire .010 inch in diameter is assembled in groups of 16, 26, 41, and 65 wires for sizes 18, 16, 14 and 12 B. & S. gage respectively. In the manufacturing operation, each wire is drawn and spooled separately. The wires are then unspooled, as they are assembled in a group for twisting and covering with insulation. Contrasted with this practice, the present invention contemplated bonded grouping of the requisite number of wires in the manner heretofore described, 16, 26, 41, and 65 copper wires, which after a series of reductions have a final diameter of 0.10 inch per wire and group sizes of 18, 16, 14 and 12 B. & S. gages respectively. Because the ultimate wire size is so small in these cases, it is desirable to have no alloy bond between the wire and the bonding material, and to effect the necessary bonding action, the zinc and/or other suitable material is placed around and between the wires which are not suitably surface conditioned for bonding by an alloying action. Where alloying action is required, chemically clean surfaces of wires are presented to the bonding metal. The greater the number of wires in a group, the smaller the size of the wire when drawing is accomplished. By handling the wires in a group for the product outlined, much scrap and much expensive handling is avoided, fewer dies are required, and production costs are materially lowered. It is obvious that with sixteen wires grouped in a single unit, only one-sixteenth as many operations are required for threading through dies, spooling, respooling, etc., as where the wires are handled individually. The chances of breakage are reduced to a minimum by the group arrangement, and the production per unit

of labor is greatly increased. After the last reduction the bonding metal is readily removed. If the wires are to be used for some other purpose than the construction of an electric cable, they may be spooled individually upon removal from the accumulation in separated condition.

The apparatus used in the application of the process may vary widely and is chosen to accord with the sequential operation to be performed. A set up of a series of six units for one application of the process is illustrated in the drawings, in which

Fig. 1 is a plan view and

Fig. 2 is a sectional view along line 1—1 of Fig. 1 of a bonding mechanism

Fig. 3 is an enlarged plan view and

Fig. 4 is an enlarged sectional view along the line 2—2 of Fig. 3 showing the final bonding units.

Fig. 5 is a sectional view of a group of round wires bonded together

Fig. 6 is an elevation in partial section of a wire drawing mechanism and of an associated separating unit for bonded wires.

Fig. 7 is a plan view of the mechanism shown in Figure 6.

Fig. 8 is a side elevation, and

Fig. 9 is a plan view of a twisting and take up mechanism.

In the sequence in which they take part in the operations, the units employed are a water bath, an acid bath 2, a bonding unit 3, a wire drawing unit 4, a debonding unit 5, and a combined twisting and take-up unit 6, the material extending from the first to the last unit in some cases, and collecting at intermediate points in other cases.

Referring to Fig. 1, a group of parallel separated wires 8 from reels not shown are passed over a guide roll 9, into a water bath 10, and under guide rolls 11 therein, then out and over guide rolls 12, into acid bath 13, and under guide rolls 14, out and over guide rolls 15 while receiving heat from plate 16, then into metal bath 17, and under guide roll 18. As the separated wires 8 pass from the roll into the metal bath they converge in the groove 19 of guidewheel 20.

From the guidewheel 20 the wires in nested relation pass angularly upwardly to an asbestos wipe 21 positioned in a die 22, then to a bonding die tapered opening 23, and on through a cooling box 24 to a power driven capstan 25 which provides the traction for drawing the wires forward from their initial positions on the reels not shown. As the wire advances on the capstan, it may be collected on pins inserted in sockets 26 or it may be withdrawn and subjected to further processing.

Considered in their broad aspects relative to the preliminaries to attenuation of a group of strips, it is seen that the steps involve the assembly of the strips in a group arrangement, the placement of supporting material between the strips, and the utilization of heat to effect the formation of the supporting material among the strips as they emerge from immersion in the supporting material. The placement of the supporting material is effected while the strips are traveling. It is also effected while the portion of the strips thereon is undergoing an attenuating operation.

Regarding the supporting material, it is seen that it must be in a condition to flow between the wires, as they travel in group relationship through the material in a container.

While zinc has been set forth as suitable support material, consideration of the operations involved shows that they are not limited to this class of material for group supporting of strips. In this respect it is seen that the material must lend itself for conditioning to flow between the wires, must be responsive to increments of heat sufficient to form a body between the wires, and must be adapted to working in a die or other attenuating apparatus. Zinc is rather recalcitrant toward working in a die at atmospheric temperatures. Heat from the bath or die conveyed with the zinc on the strips renders it amenable to the attenuating operation.

The cooperative relationship of the bonding elements are detailed in Figs. 3 and 4. A pair of elongated arms 27 are positioned at one end on pipelike pivots 28 and 29 at the exit end of the metal bath 17 so that the arms extend each along its side of the bath 17. The other end of the pair of arms is separated by a shaft 29 carrying at its mid position the guide wheel 20, and parallel to said shaft a bar 30 on the exit side of the guide wheel 20. The cross bar 30 has a tapered recess carrying die 22 and asbestos wipe 21. The pivoted ends of the arms 27 are formed into a boxlike member 31 within which is a smaller box number 32 having an intervening space 33 between box bottoms. The pipelike pivots provide passages to the smaller box 32, a valve 34 on pivot 29 providing control of flow into the box, while pivot 28 provides an exit passage. The said pivots also permit relative movement of the two boxes 31 and 32 which have the swinging ends on a bevel to accommodate such movement. The beveled ends are at right angles to the line of travel of the wire which passes through concentric openings 35 and 36 respectively in the said swinging ends. These openings are concentric with a removable die 37 provided with electrical heating elements 38 and 39 and with liquid cooling means 40 from inner box 32 through passages 36 and 35. The die 37 is mounted in a recess in a cross bar 41 having an upstanding pair of extensions 42 pivoted on pins 43 held on the upper edges of parallel arms 27. A beveled extension of the die 37 fits into a recess concentric with the recess 35 in the end of box 31 thereby forming a tight joint therebetween. The pins 43 extend into yokes 44 on the edges of bath 17 and are there held by removable pins 45 which serve to hold the bonding combination immersed in the bath 17 during bonding operations.

The asbestos wipe 21 and its die 22 also bonding die 37 are in alignment with the discharging side of the guidewheel 20 and the capstan 25, the latter driven by means not shown.

In operation the several wires 8 converging to the grooved guidewheel 20 pass in grouped relationship through the asbestos wipe 21, which cleans the external surface of the group, through grouping die 22 and on through bonding die opening 23 into contact with the cooling liquid 40 in box 32 and then on to capstan 25 which provides traction for the grouped wires.

As the wires pass through the bonding die opening 23 bath metal 17 in the die opening is congealed into the wires by proper control of the electrical heating elements 38 and 39 and of the cooling medium 40 so that the bath metal takes on the form of the exit opening of the die and encloses the wires in its embrace. Referring to Fig. 5, the wires 8 are shown completely surrounded by congealed bath metal 17.

Referring to Figs. 6 and 7 the drawing unit there shown comprises a boxlike frame 46 supporting die holders 47 with dies 48 therein, drawing drums 49, and a drive shaft 50 with intermediate gearing between the drive shaft and drums whereby the drums are rotated. A clutch 51 in the drive shaft between drum drives permits selective operation of drawing drums. The hub 61 of each drum 49 is keyed or otherwise secured to a hollow vertical shaft 52, the latter projecting upwardly through the box frame 46 and being suitably journalled in a bushing 53 by a bearing bracket 54 secured to the under side of the box top. At its lower end the shaft carries secured thereto a beveled gear 55 which is in mesh with a beveled pinion 56 that derives rotation through shaft 58 and beveled gears 59 and 60 from shaft 50. For the drawing of wire continuously additional mechanism is required to effect the passage of the wire from block to block, or drum to drum.

The shaft 52 of each block or drum has an extension 63 above the drawing drum 49 having thereon and frictionally driven thereby an arm 62 projecting beyond the periphery of the drum 49 carrying a rotatively mounted guidewheel 64. The arm 62 has a tapered bearing on the shaft 52 which is adjusted in position by ring 65 whereby to regulate the frictional engagement between the arm and the shaft. In the hollow shaft 52 is positioned a spindle 66 which carries on its upper end a drum 67 keyed or otherwise fastened thereto and on its lower end a beveled gear 68 loosely mounted thereon, and intermediate to the bevel gear 55 on the hollow shaft 52 and the loosely mounted gear 68 a friction clutch 69 keyed to the spindle and adapted by its engagement with the gear 68 to transmit motion to the upper drum 67. The lower gear 68 is driven by the same pinion 56 but in the opposite direction as the gear 55 on the upright shaft 52. Movement of the clutch 69 by a lever not shown to the disengaging position throws the clutch against a projecting stationary arm 70 with sufficient force to hold the disengaged spindle from free rotation thereby providing a brake to the drum 67. In the spindle 66 is embedded an electrical cable having at its lower end terminals on a pair of sliprings 71 and 72 in engagement with terminal brushes 73 and 74 respectively mounted on the frame 46 and providing current to the rotating cable. The upper end terminals 75 and 76 of the cable are attached to a heating coil 77 within the upper drum 67 serving to heat said upper drum in accordance with operating requirements. Adjacent to the upper drum 67 and positioned to receive wire tangentially therefrom is a guide wheel 78 on a standard 79 carrying a second guide 80 positioned to guide wire from the upper wheel on its passage to a die 48 or to a succeeding operation.

In operation the periphery of each drum receives enough coils of wire to provide the traction required for drawing the wire through the preceding die. Each drawing drum and its upper associated drum serve as variable storage drums for the wire in process of being drawn. The wire leaving the drawing drum is passed up and on the guide wheel 64 and then around the periphery of the upper drum in the reverse direction to the rotation of the drawing drum 49. Normally the guide wheel 64 through frictional connection rotates with the drawing drum 49, but is restrained by the wire in its reverse pas-

sage to the upper drum so that in effect the guide wheel transfers wire from the lower to the upper drum. The wire crowding upwardly on the upper drum there accumulates and is withdrawn therefrom by the drum's rotation with regard to the operation of the drawing drum 49.

The two drums constitute a variable accumulating device between drafts on a wire and consequently the gear ratios of the successive drawing drums in a series need not be so closely determined as is normally the practice in other machines.

With the apparatus thus far described the successive operations of bonding and simultaneously attenuating a plurality of strips is performed. From the attenuating operations the bonded wires 8 are conducted into a debonding unit 5 comprising an electrically heated furnace chamber 81 on hollow base 82. Terminals 83 and 84 supply current to the furnace. A trough like bracket 85 on base 82 carries sizing dies 86, wipes 87, and guide wheels 88 in alignment with the tablelike furnace chambers 81. Bonded wires passing from the last guide 80 of the attenuating operations enter the heated furnace 81 and in consequence of the heat gradually drop their bonding metal to the furnace bottom. The separated wires pass through asbestos wipes 87, sizing dies 86 and around guide wheels 88 to a subsequent operation. Bonding metal from the furnace bottom and wipes flows over trough bracket 85 to a receptacle not shown within the furnace base 82. The subsequent operation illustrated is a regrouping of the wires in a die 89 which is the entrance member of a twisting and coiling mechanism illustrated in Figs. 8 and 9 and duplicating the mechanism set forth in U. S. Patent 8,825 to Joslin for making cordage. This particular twisting arrangement is chosen because the takeup rotates thereby performing the twisting while allowing the wires to move only longitudinally. It comprises a stationary die 89 in a rotatably mounted yoke 90 in standards 91. A pulley 92 imparts motion to the yoke. Stationary gears 93 and 94 on opposite ends of the yoke through geared connection to ceiling drum 95 and takeup drum 96 respectively cause said drums to rotate about their axes positioned crosswise to said yoke 90. The coiling drum 95 is removably mounted through the removable shaft 97 upon which it is supported, whereby successive drums may be positioned. The operation of this twisting mechanism is contemplated to be simultaneous with the preceding units already described. The copper wires are cleaned, acid coated, immersed in zinc, bonded together, attenuated, debonded, and twisted in sequence, intermediate accumulation of the wires taking place to accommodate the rates of operation required for the successful manipulation of the material in hand.

An attempt to mention or describe all of the known or possible processes for bonding together a number of wires for their group elongation and handling through dies, and the releasing of the wires from their bonded condition, is not attempted; however, this invention is not limited to those processes mentioned or described, but embraces every method of effecting such bonding condition. Furthermore, it is not essential in this invention to employ only metal as a filler for inner cavities between wires grouped closely together, the essential requirements being that the filler material should not be appreciably com-

pressible and should be capable of extension proportionately with the wires. Also other metals than zinc may be used for bonding. The stage in the process after drawing where the release of the bonding metal is effected may be widely varied. In fact, in some cases the release of the bond is not essential; as, where a pair only of steel wires are bonded together and so drawn, patented, again drawn and then incorporated in a rope strand, the bond between the wires serving to facilitate manufacturing and to give increased life in the rope by holding either wire, should it break in proper position beside the other wire. The steps outlined in the process are capable of wide variations in application. In this connection, again refer to the first of the various means for grouping and bonding units together previously mentioned, and follow a single wire through the operations. Consider that a steel wire is being passed through a coating metal bath of zinc, through a die larger than the wire immersed in the coating metal on one face, with cooling means on the opposite face, and heating means intermediate the faces, so that solid zinc and the wire emerge from the die by reason of the die cooling, to a traction drum and into a heated accumulator above 150° F., through a series of reducing dies while above 150° F. and less than melting temperature of the zinc. These essential steps for group attenuation when operative on a single steel wire produce a new product of high strength due to absence of annealing incident to galvanizing at finish size, one with a heavy zinc coat of predetermined thickness, by reason of the die, and flexible by reason of working repeatedly at an elevated temperature, preferably above 300° F., but permissibly as low as 150° F. Just as a further example of the variations intended; consider a laminated ingot of steel prepared by taking smooth, rectangular, thinly copper coated bars two inches by two inches by six feet piled, eighty-one pieces, together to form an eighteen inch by eighteen inch ingot in an atmosphere of hydrogen heated to the vicinity of the melting point of the copper. This hydrogen copper brazing process in the capillaries between the steel bars brazes them into a solid body of laminated makeup which, when rolled into rods and drawn into wire, still retains the laminated structure. This laminated structure of the wires gives it a characteristic behavior under stress which is entirely absent from unlaminated steel wire. Repeated flexure of an unlaminated wire starts a fracture in the wire which spreads over the wire section without interruption. Repeated flexure of the laminated wire starts a fracture in the laminations one after the other just as though each lamination were a separate wire, which it is in fact, resulting in a much longer life under stress. This wire of laminated structure is also a new product, the filaments of which may be patented, tempered, annealed, twisted or otherwise manipulated in a group. When the filaments are to be separated, it is preferable that a bonding metal be used of lower melting temperature than copper. Also when a lower melting temperature metal is used its application must be suitably timed in the operations to avoid the high heat incident to rod rolling.

I claim:

1. In the process of attenuating a plurality of metal strips the steps consisting of arranging said strips in a group, progressively providing auxiliary metal from a molten state between the

adjacent surfaces of said strips in said group, adapted to support said adjacent surfaces against distortion during attenuation, subjecting the leading portion of said group to an attenuating operation while the following portion thereof receives said first operation, and separating said auxiliary metal from the leading portion of said strips while the following portion thereof receives said second operation.

2. In the process of attenuating a plurality of metal strips, the steps consisting of arranging said strips in a group, providing auxiliary metal from a molten state between the adjacent surfaces of said strips in said group adapted to support said adjacent surfaces against distortion during attenuation, subjecting the leading portion of said group to an attenuating operation, and utilizing heat for separating said auxiliary metal while the following portion thereof receives said first operation from said strips while the following portion thereof receives said attenuation.

3. In the process of attenuating a plurality of metal strips, the steps consisting of arranging said strips in a group, providing auxiliary metal from a molten state between adjacent surfaces of said strips in said group adapted to support said adjacent surfaces against distortion during drawing into wire, subjecting the leading portion of said group to attenuation by wire drawing while the following portion thereof receives said first operation, and subjecting said auxiliary metal of the leading portion of said group to heat for the removal thereof from said strips while the following portion of said group receives said attenuation.

4. In the process of attenuating a plurality of metal strips, the steps consisting of arranging said strips in a group, providing auxiliary metal from a molten state between adjacent surfaces of said strips in said group adapted to support said adjacent surfaces against distortion during drawing into wire, subjecting the leading portion of said group to attenuation by wire drawing while the following portion thereof receives said first operation, utilizing heat for the removal of said auxiliary metal from the leading portion of said strips, and winding said strips in coils while the following portion thereof receives said attenuation.

5. In the process of attenuating a plurality of metal strips, the steps consisting of arranging said strips in a group, providing auxiliary metal from a molten state between adjacent surfaces of said strips in said group adapted to support said adjacent surfaces against distortion during drawing into wire, subjecting the leading portion of said group to attenuation by wire drawing, utilizing heat for the removal of said auxiliary metal from the leading portion of said group of strips while the following portion thereof is attenuated, and subjecting the leading portion of said group of wires to a twisting and winding operation while said removal is effected on the following portion.

6. The process of producing an attenuated metal article which comprises congealing a thickness of coating metal adapted to proportionate reduction with a strip on which it congeals, retaining heat of said congealing metal in said congealing metal in said coating during a plurality of attenuations, performing a plurality of attenuations on the leading portion of said combination so heated while effecting said congealing operation on the following portion thereof, there-

by producing an attenuated article free from loss of strength due to hot coating at the final stage.

7. The process of manufacturing a twisted group of wires which comprises the steps of providing auxiliary material between adjacent surfaces of said wires in a group adapted to support them during drawing, drawing the leading portion of said group of wires and material through a reducing die while performing said first operation, releasing said material from the leading portion of said surfaces and twisting said group of wires while performing said first operation on the following portions thereof, thereby avoiding separate coiling of said wires after drawing.

10 8. In the process of attenuating a plurality of wires the steps which comprise placing between the surfaces of said wires material adapted to support them in their relation to each other during drawing and utilizing said material to substantially maintain the contour of said wires while reduction in their cross section is effected, and separating said material from the leading portion of said wires thereby making the leading portion of said wires available for individual treatment while said placing operation is effected on the following portion of said wires.

15 9. In the process of attenuating a plurality of wires the steps which comprise placing between the surfaces of said wires material adapted to support them in their relation to each other during drawing, and while performing said first operation utilizing said material to substantially maintain the contour of the leading portion of said wires while reduction in their cross section is effected in a die, and removing said material from between said wires, whereby the number of dies and the handling of the wire for the attenuation of said wires of prescribed contour are diminished.

20 10. In the process of attenuating a plurality of wires, the steps which comprise passing said wires through a metal bath and causing metal therefrom to congeal between said wires as support thereto, and while effecting said congealing operation utilizing said metal on a leading portion of said wires to substantially maintain the contour of said wires while reduction in their cross section in a die occurs.

25 11. In the process of attenuating a plurality of wires, the steps which comprise passing said wires through a metal bath and causing metal therefrom to congeal between said wires as support thereto and while placing said metal utilizing said metal on a leading portion of said wires to substantially maintain the contour of said wires while reduction in their cross section in a die occurs; and removing said metal from between said wires, whereby the number of dies for attenuating said wires is materially reduced.

30 12. In the process of attenuating a plurality of wires the steps which comprise placing between the surfaces of said wires material adapted to support them in their relation to each other during drawing and while placing said material utilizing said material on a leading portion of said wires to substantially maintain the individual contour of each wire while reduction in the cross section of said leading portion of wires is effected simultaneously in a die, and removing said material from between said wires, whereby the number of dies for drawing is reduced.

35 13. In the process of attenuating a plurality of wires the steps which comprise placing between the surfaces of said wires molten metal

and congealing said metal in said position as a support to said wires and while placing said metal utilizing said metal on a leading portion of said wires to substantially maintain the contour of said wires while reduction in their cross section occurs in a die; and removing said metal from between said wires, whereby the number of dies for reducing said plurality of wires is materially reduced.

14. In the process of manufacturing twisted wires the steps consisting of congealing molten metal between a group of wires thereby providing support between said wires; and while placing said metal utilizing said metal on a leading portion of said wires to substantially maintain the contour of said wires while reduction in cross section in a die is effected; removing said metal from between said wires; and twisting said wires, thereby avoiding coiling of said wires after drawing and reducing the number of dies for drawing.

15. In the process of manufacturing twisted copper cable, the steps comprising congealing between the wires of said cable metal adapted to support said wires in their relation to each other; and while placing said metal utilizing said metal on a leading portion of said wires to substantially maintain the individual contour of each wire while reduction in the cross section of said wires is effected in a die, and removing enough material from between said wires to permit relative movement between said wires; and twisting said wires, thereby reducing the number of dies for drawing said wires and the breakage of said wires and the separate coiling of said drawn wires.

16. The method of making a bimetal strip which consists in passing a metal strip through a bath of molten metal, beneath the surface thereof, and as it leaves the molten metal passing through a die with sectional opening greater than the section of said strip, whereby molten metal is carried with said strip, and congealing said molten metal on said strip before it emerges from said die, said congealing metal being of a character such as to require a temperature above the normal atmosphere in order that during further working said metal may acquire pliability, and working said strip at said temperature.

17. In the process of producing an attenuated metal article, the steps consisting of immersing the entrance of a die in a bath of metal adapted to congeal on a metal strip, progressively congealing metal from said bath upon a strip extending through said die, and utilizing the congealed metal on said strip to limit the flow of congealing metal from said die, said congealing metal being of a character such as to require a temperature above the normal atmosphere in order that during further working said metal may acquire pliability, and working said strip at said temperature.

18. In the process of producing an attenuated metal article, the steps consisting of immersing the entrance of a die in a bath of metal adapted to congeal on a metal strip, progressively congealing metal from said bath upon a strip extending through said die, progressively utilizing the congealed metal on said strip in the exit orifice of said die to control the flow of metal from said bath and heating the metal in the entrance of said die to control the friction of the metal congealing therefrom.

19. In the process of drawing wire the steps comprising providing minute temperature increases in a die by electrical heating and minute temperature decreases by refrigeration thereby controlling the surface condition of wire progress-

ing through said die, and immersing one face of said die in a bath of a liquid adapted to form the said surface on said progressing wire.

20. In the process of producing an attenuated metal article, the steps consisting in heating the tapered passage in a die and zinc therein adapted through heat to act as a lubricant upon a strip therein and utilizing said zinc while heated on said strip to facilitate its passage through a plurality of dies.

21. In the process of producing an attenuated metal article, the steps consisting of heating a metal strip to a temperature approaching molten metal adapted to congeal thereon, progressively congealing metal in a passage around said strip thereby bonding the metal to said strip, utilizing said congealed metal on said strip to limit the flow of congealing metal through said passage and regulating the temperature of said passage thereby to control the friction of said congealed metal in its movement.

22. In the process of producing an attenuated metal article the steps consisting of progressively congealing metal in indentures in the cross sectional contour of strip material, progressively attenuating the leading portion of said strip and congealed metal while performing said congealing operation on the following portion of said strip, and removing said congealed metal from said strip thereby preserving said indentures.

23. In the process of producing a uniform coating of a thickness heavier than an air cooled dipped product on a core strip, the steps consisting of progressively congealing said coating material in a die by contact with a liquid as said strip emerges from a bath of said coating material, and progressively sizing said coating thickness by said congealing operation.

24. In the process of producing a uniform zinc coating of a thickness heavier than an air cooled dipped product on a core wire, the steps consisting of progressively congealing said zinc in a die by contact with a liquid as said wire emerges from a bath; sizing said coating thickness by said congealing operation, and utilizing the residual heat in said congealed metal to facilitate its passage through an attenuating device.

25. In the process of producing a uniform zinc coating of a thickness heavier than an air cooled dipped product on a core wire, the steps consisting of progressively congealing said zinc in a die by contact with a liquid as said wire emerges from a zinc bath, and utilizing the residual heat in said congealed zinc to facilitate its passage through an attenuating device.

26. In the process of attenuating metal wires the steps which comprise attenuating a leading section of a group of wires; providing supporting material between the following section wires of said group; and progressively actuating said wires to said attenuating operation in which said supporting material is utilized to secure proportionate reduction of said wires in the group.

27. In an attenuating process for metal strips the steps comprising actuating said strips as a group progressively through trailing, middle and leading sections; providing supporting material between said wires in said trailing section; attenuating said wires in said middle section wherein said supporting material is utilized to secure proportionate reduction of said wires; and coiling said wires in said leading section.

28. In the process of manufacturing twisted wire cable, the steps consisting of attenuating a portion of said wires with supporting material be-

tween them by drawing through a die; twisting a leading attenuated portion of said wires into a cable; and winding the twisted wires into coils, thereby eliminating intermediate handling between drawing and twisting.

29. In the process of attenuating a plurality of wires in a group the steps comprising providing

supporting material between said wires as they enter an attenuating die for reduction, passing said wires through said die; separating said wires from each other; and coiling said wires, whereby said wires are attenuated with their original cross sectional outline.
